United States Patent Office

Des. 227,278

Patented June 12, 1973

227,278

PEDAL EXERCISER

Oscar T. Arato, 25 Kensington Ave.,
Willowdale, Ontario, Canada

Filed Nov. 26, 1971, Ser. No. 202,049

Term of patent 7 years

Int. Cl. D21—02

U.S. Cl. D34—5 K

FIG. 1

FIG. 2

FIG. 3

FIG. 4

FIG. 1 is a front perspective view of a pedal exerciser showing my new design;

FIG. 2 is a rear elevational view thereof;

FIG. 3 is a left end elevational view thereof; and

FIG. 4 is a top plan view thereof.

I claim:

The ornamental design for a pedal exerciser, as shown.
